UNITED STATES PATENT OFFICE.

KARL FRIEDRICH EBEL, OF SINGEN, GERMANY.

STIRRUP.

No. 888,699.

Specification of Letters Patent. Patented May 26, 1908.

Application filed December 31, 1907. Serial No. 408,763.

To all whom it may concern:

Be it known that I, KARL FRIEDRICH EBEL, a subject of the German Emperor, and resident of Singen, Durlach district, Baden, 5 Germany, have invented certain new and useful Improvements in Stirrups, of which the following is a specification.

This invention relates to an improved stirrup of the self-opening type, which is shown 10 on the accompanying drawing in Figures 1 & 2 in an elevation and sectional plan respectively.

The stirrup comprises two equal members a^1, a^2 which are hingedly connected by a pivot 15 b so as to form, when in position of use, the base or tread a . Each member possesses a separate stirrup leather or strap c, c^1 so as to be able to move independently from each other. In order to keep the members in the 20 normal position of use, the pivot b is surrounded by a spring d which has on both ends extensions to act on the lower side of both members.

Upon the rider falling off the horse, the

stirrup, being released from the pressure of 25 the foot on its base or tread, opens on account of the foot pressing now on the upper part of the stirrup whereby the action of the spring is overcome.

Having fully described my invention, what 30 I claim and desire to secure by Letters Patent is:—

A stirrup, comprising in combination two equal stirrup members, a pivot to hingedly connect said members at their base, a spring 35 on said pivot having on both ends extensions to act on the lower side of both members so as to keep them in the normal position of use, and means at the upper end of each member for engagement with a stirrup leather, for the 40 purpose set forth.

In testimony whereof I have hereunto set my hand in the presence of two subscribing witnesses.

KARL FRIEDRICH EBEL.
